PRODUCTION OF GAS AND COMBUSTION
THEREOF

Archer E. Knowlton, Short Beach, Conn.

Application June 13, 1935, Serial No. 26,495

9 Claims. (Cl. 204—5)

The invention relates to separating water into its component gases and subsequently recombining the gases into water and utilizing the heat generated by the combining combustion.

It is well known that when a continuous electrical current is passed through water it will be electrolyzed and will be separated into hydrogen and oxygen, one gas coming off at one electrolytic pole and the other gas coming off at the other electrolytic pole. The gases so produced may be stored together or separately and subsequently brought together in proper proportions and ignited and burned. The ignition and combustion liberates a large amount of heat. Water is the sole product of the combustion process and the water produced by the combustion may be returned to the original body of water. By this means it is possible when operating in a closed system to repeatedly use a single quantity of water which is not decreased or increased. Such a system may be sealed and aside from unusual or unexpected leaks may continue to operate without additions and without attention for considerable periods.

The present invention contemplates the employment of such operation for the production of useful work or desirable results.

Various control mechanisms may be associated with the apparatus so as to produce a mechanism which will have its operation initiated and stopped at appropriate times. This may be done automatically or manually or partially automatically or partially manually.

The specific purpose to which the invention is devoted and the useful end in view is not confined to a single operation. The heat of the combustion may be used for many purposes. A closed system is not essential but may have advantages. To illustrate a specific application of the invention there is here shown and described an embodiment of a closed system constituting a means for heating water in a tank which water may be used for any suitable or desired purpose.

Said storage of combustible gases without loss for subsequent combustion when heat is desired averts the dissipation through insulation of the heat from masses which it is desired to maintain in a heated state for extraction at intermittent intervals.

In the accompanying drawing is shown in somewhat diagrammatic form apparatus for carrying out the invention.

A tank 1 is provided which is partially filled with water 2. The amount of water in the tank is immaterial although if desired it may be near-

ly filled with water at the beginning of the operation.

Electrical conductors 3 and 4 may be employed to bring electricity to the apparatus. The current introduced by the conductors 3 and 4 may be direct or alternating current. In the drawing it is assumed that alternating current is supplied. The conductor 3 is connected at 5 to a rectifier 6 and the conductor 4 is connected at 7 to the rectifier 6. On its direct current side 10 the rectifier 6 is connected at 8 to an electrode 9 in the water 2 in the tank 1 and at 10 it is connected to an electrode 11 also in the water 2 in the tank 1. A partition 12 is illustrated extending across the tank 1 between the electrodes 9 and 11. The partition 12 extends downward from the top of the tank 1 but stops short of the bottom of the tank 1 so that the water may seek its level across the tank. Between the contact 10 and electrode 11 is shown a toggle switch arm 13 controlled by a pressure-responsive device 14 here shown as in the water 2 in the tank 1. Any suitable pressure mechanism may be employed. The device illustrated comprises a rod 15 engaging the lever 13 by a slot 25 and pin mechanism 16. Around the stem or rod 15 is a coil spring 17 which tends to expand a metallic bellows 18 and hold the lever 13 against the contact 19 so as to make electrical connection between the electrode 11 and the contact 10 of the rectifier 6. When the switch is closed current passes between the electrodes 9 and 11, through the water 2 and electrolyzes or decomposes the water. When it is desired to keep the gases separate some such device as the baffle 12 35 may be employed although this separation is not essential. Oxygen is freed at the electrode 9 and collects under pressure above the water in the upper portion of the tank 1 to the right of the partition 12. Hydrogen is freed at the electrode 11 and collects under pressure above the water at the upper portion of the tank 1 to the left of the partition 12. Since twice as much hydrogen is produced as oxygen it is preferable to have the partition 12 so placed as to leave 40 twice as much space at the left as at the right. The gases as freed are at more than atmospheric pressure and as the pressure of the accumulated freed gases builds up it tends to cause the metallic bellows 18 to collapse and thus forces open 50 the switch lever 13 against the pressure of the spring 17. Thus the electrolytic decomposing of the water is stopped when sufficient gas has assembled under pressure to the point for which the apparatus may be set. The reservoir of gas 55

and the pressure may be fixed at any practical limits as controlled by the character of the tank and other parts subjected to the pressure.

Associated with the tank 1 is a tank 20 shown 5 as provided at its bottom with an inlet pipe 21 and at its top an outlet pipe 22. Suitable valves, not shown, may be associated with the pipes 21 and 22 so as to allow water to enter the tank 20 and to be withdrawn therefrom. Within the tank 10 20 is a closed chamber 23 which may be referred to as a bomb. Within the chamber 23 is a burner 24 to which leads a pipe 25 to which are joined pipes 26 and 27. The pipe 26 leads from the upper portion of the tank 1 at the right of the partition 12 and thus may conduct oxygen to the burner 24. The pipe 27 leads from the upper portion of the tank 1 at the left of the partition 12 and thus may conduct hydrogen to the burner 24. The pipes 26 and 27 are diagrammatically illustrated 15 by similar lines. It may be desirable, however, to have the pipe 27 twice as large as the pipe 26 so as to bring the gases in proper proportions to the pipe 25 and thus to the burner 24. In the pipe 26 is a valve 28 and in the pipe 27 is a similar valve 29. The valve 28 is illustrated as controlled by a solenoid 30. The valve 29 is illustrated as controlled by a solenoid 31. The solenoids 30 and 31 are connected in parallel to a circuit which is controlled by the toggle switch lever 32. The 20 switch 32 is controlled by a thermostatic device such as the bi-metallic strip 33 fastened to one side of the tank 20. The current for the solenoids 30 and 31 may be traced from the conductor 34 to the contact point 35 through the conductor 36 past the contact point 37 through the conductor 38 to the switch lever 32 through the conductor 39 through the solenoids 30 and 31 through the conductor 40 to the contact point 41 and through the conductor 42 to the 25 conductor 4. Extending through the wall of the tank 20 and into the bomb 23 is illustrated an insulated ignition plug 43. The ignition plug 43 is connected to a spark coil 44 controlled by a switch 45, illustrated as a manually controlled switch leading to the contact point 37 and so to the conductor 3. The other side of the coil 44 leads through the conductor 46 to the contact point 47 and thence through the conductors 48 and 42 to the conductor 4. Leading from the 30 bomb 23 is a pipe 49 which may carry the water produced by the combustion of the gases in the burner 24 into the water 2 in the tank 1. In as much as the gases in the tank 1 may produce considerable pressure it may be desirable to provide a check valve 50 in the pipe 49 which will allow water to go toward the tank 1 but not toward the bomb 23. As an aid in the flow of the water through the pipe 49 there may be provided a pump 51 which is illustrated as operated by a small electric motor 52 connected across the conductors 3 and 4 at the contact points 35 and 41.

Suitable switching mechanism may be provided for this motor 52 and suitable switching mechanism may be provided for the conductors 3 and 4 as well as for other elements shown.

On the pipe 26 between the valve 28 and the tank 1 is a pipe 53. On the pipe 27 between the valve 29 and the tank 1 is a pipe 54. The pipes 53 and 54 lead to a pipe 55 extending into the bomb 23 and provided with a small orifice 56 which may act as a permanently burning pilot light for the burner 24. These may be suitably controlled by valves etc.

It will be understood that when initially started 75 the gases will be generated but there will be no

combustion until ignition initiates it. By closing switch 45 the pilot flame can be ignited and will then continue burning indefinitely or until it is purposely extinguished. The flame can be restarted at any time by closing the switch 45. In 5 the initial condition of the operating cycle the water in the tank 20 will be cold and the thermo-strip 33 will allow the switch 32 to be closed. This will cause the valves 28 and 29 to be opened allowing hydrogen and oxygen to pass to the burner 10 24. The pilot burner 56 being lighted, the gases in the burner 24 will be ignited. As the combustion proceeds the water in the tank 20 may become heated and the thermo-couple 33 will cause the switch 32 to be expanded as illustrated in the 15 drawing. This will deenergize the solenoids 30 and 31 to allow the valves 28 and 29 to be closed causing the ignition in the burner 24 to cease. When the heated water is withdrawn from the tank 20 or when the water in the tank 20 becomes 20 cold the switch 32 may close and again start the ignition. As it is formed the product of the combustion at the burner 24 condenses into water in the bomb 23 and is withdrawn through the pipe 29 and returned to the water 2 in the tank 1. 25 The electrodes 9 and 11 cause water to be separated from the hydrogen and oxygen until sufficient of the gas is stored in the upper part of the tank 1 to increase the pressure sufficiently to cause the switch 13 to open when the electrolysis will be discontinued until sufficient gas has been withdrawn to the burner 24 to reduce the pressure sufficiently to allow the spring 17 to close the switch 13 and again initiate the electrolytic action. The gases are thus stored up for use as 30 may be needed for the sake of the heat to be derived from their combustion.

Various changes in structure and operation in the illustrative apparatus may be made in carrying 40 the invention.

I claim as my invention:

1. The method of heating fluid comprising partially filling with water a tank having electrodes in the water and a partition above the water and extending thereinto and between the 45 electrodes, conducting electricity to the electrodes to separate the water into hydrogen and oxygen, collecting the gases separately on opposite sides of the partition, leading the gases to a burner within a closed chamber surrounded by the fluid to be heated, igniting the gases at the burner, controlling the flow of gases to the burner in accordance with the heating of the fluid, controlling the flow of electricity to the electrodes in accordance with the pressure of 50 the gases in the tank, and returning the products of the combustion to the tank.

2. A tank partially filled with water, electrodes in the water which when continuous electric current passes between them will break down 60 the water into hydrogen and oxygen, a partition above the water and extending thereinto and between the electrodes, conduits from the spaces above the water on both sides of the partition, valves in the conduits, solenoids arranged when energized to operate the valves, a conduit connecting the said conduits, a burner to which the last named conduit extends, a pipe connected with the spaces on both sides of the partition above the water, a pilot light to which the pipe leads and adjacent the burner, a spark plug adjacent the pilot light and burner, a closed chamber surrounding the burner, the pilot light and the spark plug, a conduit leading from the closed chamber to the tank, a pump in the last named 65

5 conduit, a check valve in the last named conduit, a closed receptacle enclosing the chamber, means for leading fluid to and from the receptacle and into contact with the chamber, means associated with the receptacle for operating the solenoids in response to the temperature of the receptacle and means associated with the tank for controlling electric current between the electrodes in response to the pressure within the

10 tank.

3. A tank partially filled with water, electrodes in the water which when electric current passes between them will break down the water into hydrogen and oxygen, a partition above the water and extending thereinto and between the electrodes, conduits from the spaces above the water on both sides of the partition, valves in the conduits, a conduit connecting the said conduits, a burner to which the last named conduit extends, a pipe connected with the spaces on both sides of the partition above the water, a pilot light to which the pipe leads and adjacent the burner, a spark plug adjacent the pilot light and the burner, a closed chamber surrounding the burner, the pilot light and the spark plug, a conduit leading from the closed chamber to the tank, a pump in the last named conduit, a check valve in the last named conduit, a closed receptacle enclosing the chamber, means for leading fluid to and from the receptacle and into contact with the chamber, means associated with the receptacle for operating the valves in response to the temperature of the receptacle, and means associated with the tank for controlling electrical current between the electrodes in response to the pressure within the tank.

4. A tank partially filled with water, electrodes in the water which when continuous electric current passes between them will break down the water into hydrogen and oxygen, storage means above the water, conduits from the storage means, valves in the conduits, solenoids arranged when energized to operate the valves, a conduit connecting the said conduits, a burner to which the last named conduit leads, a spark plug adjacent the burner, a closed chamber surrounding the burner and the spark plug, a conduit leading from the closed chamber to the tank, a check valve in the last named conduit, a closed receptacle enclosing the chamber, means for leading fluid to and from the receptacle and into contact with the chamber, means associated with the receptacle for operating the valves in response to the temperature of the receptacle, and means associated with the tank for controlling electrical current between the electrodes in response to the pressure within the tank.

5. A tank partially filled with water, electrodes in the water which when continuous current passes between them will break down the water into hydrogen and oxygen, storage means above the water, conduits from the storage means, valves in the conduits, solenoids arranged when energized to operate the valves, a conduit connecting the said conduits, a burner to which the last named conduit leads, a spark plug adjacent

the burner, a closed chamber surrounding the burner and the spark plug, a conduit leading from the closed chamber to the tank, a check valve in the last named conduit, a closed receptacle enclosing the chamber, and means for leading fluid to and from the receptacle and into contact with the chamber.

6. A system of storing and using energy comprising a body of water, means adapted to electrolyze the water at a certain rate into its constituent gases under pressure, means for causing said gases to be stored under pressure, means for causing the electrolysis of the water into its gases to be arrested when the stored gases reach a predetermined condition, a combustion chamber, means for causing and permitting said gases to burn in said combustion chamber, a body to be heated by the heat of said combustion, means for controlling the burning of said gases in accord with the heat requirements, and means for returning the products of combustion to the body of water.

7. A system of storing and using energy comprising a body of water, means adapted to electrolyze the water into its constituent gases under pressure at a substantially constant rate over relatively long periods, means for causing said gases to be stored under pressure, means for causing the electrolysis of the water into its gases to be arrested when the stored gases reach a predetermined condition, a combustion chamber, means for causing and permitting said gases to burn in said combustion chamber at a relatively high rate during relatively short periods, a body to be heated by the heat of said combustion, means for controlling the burning of said gases in accord with the heat requirement, and means for returning the products of combustion to the body of water.

8. A system of storing and using energy comprising a body of water, means adapted to electrolyze the water at a certain rate into its constituent gases under pressure, means for causing said gases to be stored under pressure, means for causing the electrolysis of the water into its gases to be arrested when the stored gases reach a predetermined condition, a combustion chamber, means for causing and permitting said gases to burn in said combustion chamber, a body to be heated by the heat of said combustion, means for controlling the time and intensity and duration of said combustion in accord with the heat requirements, and means for returning the products of combustion to the body of water.

9. A method of heating a fluid comprising subjecting a body of water to electrolysis to produce oxygen and hydrogen under pressure, maintaining the gases under the generated pressure, generating further gases in response to diminution of gas pressure below a predetermined minimum, combining and igniting the gases, transferring the resultant heat to a fluid to be heated, and interrupting and initiating the combustion responsive to the condition of the fluid to be heated.
